CLAIM

The ornamental design for a towel bar support, as shown.

DESCRIPTION

FIG. 1 is a front elevational view of a towel bar support incorporating my new design.

FIG. 2 is a side elevational view as seen from the right of FIG. 1.

FIG. 3 is a bottom plan view thereof.

FIG. 4 is a sectional view looking in the direction of the arrows on line 4—4 of FIG. 1;

FIG. 5 is a sectional view looking in the direction of the arrows on line 5—5 of FIG. 1.
